ABSTRACT OF THE DISCLOSURE

Methods and compositions for topical application of an indomethacin-methylsalicylate formulation for the treatment of inflammation.

This invention is concerned with the topical application of indomethacin. Over the years, many forms of therapy have been suggested for the treatment of inflammatory disorders. One of the most effective therapeutics is indomethacin [1 - (p-chlorobenzoyl)-5-methoxy-2-methyldole-3-acetic acid], a non-steroid chemical compound that has been widely recognized for its outstanding anti-inflammatory anti-pyretic and analgesic properties. Its chemical structure is as follows (see Shen et al., U.S. Pat. 3,161,654):

Indomethacin's unique chemical structure differentiates it from the salicylates, corticosteroids, phenylbutazone-like compounds and colchicine. Unlike corticosteroids, it has no effect on pituitary or adrenal function and accordingly does not manifest the adverse side effects associated therewith. Oral administration of indomethacin has previously been reported as effective in relieving pain, reducing fever and providing increased mobility in patients with inflammatory disorders including those of a rheumatic nature. When orally administered, the drug behaves as a systemic medicine and passes into the blood stream for general distribution in the body. As is the case with numerous other drugs, not everyone can satisfactorily accept this drug via the oral mode of administration, particularly over extended periods of therapy.

It is one object of this invention to provide a method of administering indomethacin which avoids the disadvantages of oral administration.

Another object of this invention is to provide a carrier vehicle for the topical application of indomethacin whereby both local and systemic treatment of inflammation in mammals, including warm-blooded animals, such as mice, rats, horses, dogs, cats, etc., is achieved.

In accordance with this invention it is found that indomethacin can be administered by applying topically a solution of the drug in a methylsalicylate vehicle. In addition to providing highly effective relief with respect to local inflammation, topical application of the indomethacin-methylsalicylate formulation results in systemic treatment of inflammatory disorders. It is believed that the skin, in the presence of the topical formulation, acts

as a reservoir absorbing large amounts of the drug and releasing it slowly to other tissues. In this respect it is believed that the skin may act as a depot or reservoir for the indomethacin. It is theorized that the methylsalicylate, in addition to assisting in the solubilization of the drug, also enhances the absorption of indomethacin through the skin and accordingly permits the drug to be employed topically for inflammation of the tendons and joints, etc.

Methylsalicylate has been widely used for many years, 10 formerly under the name of oil of wintergreen, for its counter-irritant action in various liniments. Methylsalicylate is produced synthetically or is obtained by maceration from the leaves of *Gaultheria procumbens* or from the bark of *Betula leuta*. It has been reported that it is impossible to distinguish between the synthetic and natural oil.

Although the indomethacin may be advantageously applied topically to the skin with only methylsalicylate as the vehicle carrier, further inclusion in such formulation of non-toxic solvents, surfactants, emollients, etc., 20 which are miscible with the methylsalicylate, may be employed. Included among the materials suitable for this purpose are the following: ethanol, isopropyl alcohol, 2-octyl dodecanol, methyl pyrrolidone, glycerin, squalene, 25 isopropyl myristate, Ceraphyl 230 (disopropyl adipate), acetulan (acetylated lanolin alcohols), polyethylene glycol, dimethylsulfoxide, diethyl phthalate, dimethylacetamide, polysorbate 80 and diisopropyl adipate.

30 Mixtures of the above ingredients may also be combined with the indomethacin-methylsalicylate combination.

In addition, one may combine topical anaesthetics and 35 analgesics with the indomethacin-methylsalicylate formulation. Representative members of this class that may be combined with the formulation include alkaloids such as cocaine, benzocaine, procaine, dibucaine, lidocaine, laro- 40 caine, cyclomethylcaine, naepine, etc. If desired, the non-toxic solvents, surfactants, etc., described above may also be included in this formulation.

45 The concentration of the indomethacin in the methylsalicylate is not critical and will depend, as one skilled in the art will appreciate, upon a variety of factors including the age, body weight, the severity of the disorder being treated, etc.

50 Topical application of a formulation containing from about .1 to 20 mg. of indomethacin per ml. of methylsalicylate vehicle is effective in the treatment of inflammatory disorders with optimal effects being obtained with topical formulations containing from about 1 to about 10 mg. of indomethacin per ml. of methylsalicylate vehicle.

55 As indicated above, the amount applied topically for either local treatment or a systemic response will vary depending upon a number of considerations. In this regard, the art further appreciates that in many instances a relatively strong concentration or more frequent application of a weaker concentration may be equally effective. The objective in all cases is to obtain the maximum therapeutic response with minimum dosage.

60 For example, topical application daily of from about .5 mg./kg. to 20 mgs./kg. of the formulations described above (based upon the weight of indomethacin) are effective in the treatment of local and systemic inflammation.

65 As indicated above, it is highly desirable to add a substance such as ethanol or propanol to the indomethacin-methylsalicylate to assist in the solubilization of the drug. It will be appreciated that surfactants and solubilization agents other than alcoholic materials may be used in this respect. Where it is found desirable to add an agent of this nature, this ingredient may be present in amounts ranging from about 50% to about 90% based upon the

total weight of the methylsalicylate-containing vehicle. The concentration of topical analgesic or anaesthetic may vary from about 5% to about 20% based upon the total weight of the methylsalicylate containing vehicle.

In addition to compositions containing indomethacin and methylsalicylate, the following are representative examples of vehicle formulations which include solubilizers, analgesics, anaesthetics, etc.:

A

Percent

Ethanol -----	54
Ceraphyl-230 -----	36
Methyl salicylate -----	10
containing 2.5 mg. Indomethacin per ml. of vehicle.	

B

Percent

Ethanol -----	50
Methyl salicylate -----	10
Polysorbate 80 -----	15
Ceraphyl-230 -----	5
Water -----	20

containing 2.0 mg. of Indomethacin per ml. of vehicle.

C

Percent

Ethanol -----	10
Methyl salicylate -----	10
Squalene -----	80

containing 2.0 mg. of Indomethacin per ml. of vehicle.

D

Percent

Ethanol -----	17
Squalene -----	68
Methyl salicylate -----	15

containing 2.0 mg. of Indomethacin per ml. of vehicle

E

Percent

Ethanol -----	5
Methyl salicylate -----	5
Squalane -----	90

containing 10.0 mg. of Indomethacin per ml. of vehicle.

F

Percent

Ethanol -----	10
Methyl salicylate -----	30
Squalane -----	60

containing 2.5 mg. of Indomethacin per ml. of vehicle.

G

Percent

Isopropyl alcohol -----	28.34
Methyl salicylate -----	1.66
Isopar M -----	70

containing 3.2 mg. of Indomethacin per ml. of vehicle.

H

Percent

Isopropyl alcohol -----	25
Methyl salicylate -----	5
Isopar M -----	70

containing 6.2 mg. of Indomethacin per ml. of vehicle.

I

Percent

Isopropyl Alcohol -----	15
Methyl Salicylate -----	15
Isopar M -----	70

containing 2.0 mg. of Indomethacin per ml. of vehicle.

75 424-274

Percent

Ethanol -----	25
Methyl salicylate -----	75
containing 20 mg. of Indomethacin and 10 mg. of benzocaine per ml. of vehicle.	

K

Percent

Methyl salicylate -----	10
Ethanol -----	90
containing 5.0 mg. of Indomethacin and 2.0 mg. of benzocaine per ml. of vehicle.	

15 The formulations of this invention may be prepared employing techniques well known in the art. For example, solutions of up to approximately 10% may be prepared by mixing the indomethacin in methylsalicylate and warming with tap water or in a water bath (approximately 60° C.). The additional ingredients to be included in the formulation may be combined therewith. In addition to solutions, the formulation of the invention may be administered topically as lotions, creams, ointments, salves, etc.

25 The anti-inflammatory reaction to the topical administration of indomethacin in a methylsalicylate vehicle is nonspecific and occurs whether the injuring agent or stress be physical or chemical. Moreover, a favorable response is induced by the topical application of the indomethacin-methylsalicylate formulation not merely when the inflammatory reaction is localized but also when the condition is more extensive and the reaction is systemic. Accordingly, it should be noted that topical application of indomethacin in a methylsalicylate formulation provides not merely beneficial effects in the treatment of inflammatory disorders affecting the skin, but relief is obtained in the treatment of diseases involving inflammation of the muscles and joints.

35 As indicated previously, the indomethacin-methylsalicylate combination may be administered topically to achieve local and/or systemic effect. This is in sharp distinction with conventional orally administered anti-inflammatory agents which are either ineffectual in relieving local disorders when applied topically; or if effective in the treatment of local inflammation, the topical administration of the drug is of negligible significance in the systemic treatment of conditions requiring such therapy. For example, the literature reports that the normal, conventional local application of hydrocortisone ointment does not produce an effective systemic response. Systemic therapy is of course of preferred when the inflammation 45 involvement is extensive. Topical application of the formulation of this invention provides the unexpected and unobvious advantages of both local and systemic therapy.

What is claimed is:

55 1. The method of administering indomethacin to a patient afflicted with inflammation which comprises the topical application of a formulation comprising an effective amount of indomethacin in methylsalicylate.

2. The method of claim 1 wherein the formulation contains a solubilizer.

60 3. The method of claim 2 wherein the solubilizer is an alcohol.

4. The method of claim 3 which further contains an anaesthetic or analgesic.
